UNITED STATES PATENT OFFICE.

MURRAY SCHENCK, OF MIDDLETOWN, OHIO, ASSIGNOR, BY MESNE ASSIGNMENTS, TO
THE CERAMIC MACHINERY COMPANY, OF HAMILTON, OHIO.

FEEDING AND DUSTING DEVICE FOR COATING-MACHINES.

940,737.

Specification of Letters Patent. Patented Nov. 23, 1909.

Application filed May 10, 1907. Serial No. 372,885.

To all whom it may concern:

Be it known that I, MURRAY SCHENCK, a citizen of the United States, residing at Middletown, in the county of Butler and 5 State of Ohio, have invented certain new and useful Feeding and Dusting Devices for Coating-Machines, of which the following is a specification.

My invention relates to mechanism for 10 cleaning and feeding tile or other similar objects, and is especially intended to be used in supplying tile rapidly to an automatic machine which applies coating to them. Certain parts of my invention may be used for the 15 purpose of feeding tile only, and certain parts may be used for cleaning tile only, but since these two operations are usually essential in the art of coating tile I generally combine the parts and functions in one 20 mechanism.

My feed and dusting machine is adapted 25 to supply tile to the receiving belt or apron of an automatic coating machine which carries tile to the coating device. If the tile are placed upon this apron by hand the service of more than one operative—usually 30 several—is required, the tile are usually not distributed evenly upon the apron and it is practically impossible to feed tile up to the capacity of the machine. Further, to obtain 35 the best results tile must be dusted before coating is applied and this has heretofore been done by hand requiring service of many operatives. With my invention the tile are 40 dusted more thoroughly than is possible by hand labor and with any desired rapidity within reasonable limits.

In the accompanying drawing an exemplifying structure in which the invention is 45 embodied is shown in diagrammatic form.

Figure 1 is a diagrammatic vertical longitudinal section of a machine embodying my invention; Fig. 2, a diagrammatic elevation of the feeding and dusting machine connected with a tile coating machine; Fig. 3, a detail transverse sectional view of the chains, housings, and one of the cross-bars; Fig. 4, a detail in longitudinal section through the tile holder showing also the 50 feed belt and brushing apron; and Fig. 5 is a plan view of a section of the tile holder or box.

1 is a box, sometimes called a feed box, open at top and bottom, in which one or 55 more stacks of tile are placed. It is usually

arranged to hold several stacks side by side and for this purpose may be provided with removable or adjustable partitions 2 to properly separate tile of different widths. The tile 3 are placed in the box in stacks 60 with the faces which are to be coated downward. An apron, sometimes called a brushing apron, 4 runs over spools or pulleys 5 in the direction of the arrow and passes below the box at a distance about equal to 65 the thickness of a tile. To tighten the apron an idler 6 may be provided. Apron 4 is conveniently made of carpet or other fabric having a pile, the pile surface being placed outward. The apron serves, as will 70 later appear, to brush the surface of the tile, and the character of the material may be varied to suit special requirements. In cases where the machine is used only to feed tile the apron may be of any suitable material 75 with or without a pile surface. A support 7 is in some cases placed below the brushing apron and under the box to support the apron. This support may be a flat plate as shown, a series of rollers, or other suitable 80 device. The support may be entirely dispensed with, however, if desired.

8 is the general designation of the positive feed device which for convenience I sometimes term a feed belt. In the exemplification shown it consists of two chains 9, passing over sprockets 10, two near each end of the machine, each pair of sprockets having their teeth alined so that links of the two chains are maintained in opposite relation. 85 At suitable intervals sockets 11 are provided on the inner faces of the chain blocks. These sockets receive pins or journals 12 at the ends of cross-bars or spokes 13 which are spaced a suitable distance apart longitudinally of the chains, depending upon the dimensions of the tile being fed. Bars 13 are of smaller diameter than the thickness of a tile. To prevent lateral separation of the chains they are in a preferred construction run 100 through housings 14 a part of the distance of their travel on the line of feed. Rails 15 at the bottom of the housings are straddled by the side links of the chains and prevent lateral movement thereof. Below the line 105 of feed the chains are free except where they pass around idler sprockets 16 which may be employed if desired for taking up slack, and at their free points, as for instance at 17, the two chains may be pulled 110

apart so as to free pins 12 from sockets 11 and so remove cross-bars 13 for purposes of readjustment. In order to adjust the cross-bars a good many more sockets 11 may be provided on the chains than the number of bars usually employed requires so that various spacings of the bars may readily be obtained. The feed belt 8 is driven in the direction of the arrow (in the opposite direction to that of brushing apron 4) by any suitable means.

Suppose the brushing apron 4 and feed belt 8 to be in motion and the parts to be in the position shown in Fig. 1. The stack of tile 3 rests upon apron 4 and since the apron is moving to the left as seen in the figure, the ends of the tile are urged against the left hand end of box 1. The cross-bar 13 just to the left of the box moves with the belt and encounters the left end of the lowest tile in the stack which is below and free from the box. The continued movement of the cross-bar carries the lower tile with it, against the direction of movement of apron 4. The outer surface of the apron during this movement brushes the lower surface of the tile, effectively removing dust and dirt therefrom. As the lower tile moves to the right those above it in the stack also move in the same direction and approach the right hand end of box 1. When the right hand ends of the tiles encounter the end of the box the upper tiles cease to move and the lower one is pulled from under the stack. After the left hand or rear end of the moving tile passes the center of the stack the rear ends of the tile in the stack drop upon the apron 4. As the rear end of the moving tile approaches the forward end of the box the other tile assume approximately the position shown in Fig. 4. Were apron 4 or other support provided for the tile stationary the tile would have a tendency to remain in the position shown in Fig. 4; that is the lowest tile in the stack would in many cases not drop clear of the box, and proper feeding would be difficult or impossible. By reason of apron 4 moving toward the left, however, as soon as the weight of the stack rests upon it the stack commences to move again toward the left so that it is carried away from the rear end of the box; the rear end of the moving tile shortly thereafter passes away from the box and the rear ends of the stack drop so that the tile in the stack resume horizontal positions with the lower surface of the lower tile flat upon apron 4. Further movement of the apron carries the stack into contact with the front end of the box and the operation is repeated indefinitely, each cross-bar 13 carrying a tile before it.

It is to be understood that while only one stack of tile has been referred to, if several

stacks are placed in the box the cross-bars 65 will remove several tile at a time instead of one, and that the actions of the several stacks will be the same as that of the stack described.

The length of the box, as shown in Figs. 70 1 and 2, is somewhat exaggerated. The length of the box may be considerably varied in relation to the length of the tile, but in any event it should exceed the length of the tile sufficiently to permit the apron 4 to free 75 the stack after the removal of each successive tile in the manner described.

Cross-bars 13 may be spaced apart longitudinally of belt 8 a sufficient distance so that after the removal of a tile and the stack 80 has encountered the rear end of the box, apron 4 may move a considerable distance and by contact with the lower tile brush it considerably before the approaching cross-bar engages the tile. By another arrangement only a slightly greater distance may be provided between the cross-bars than the length of the tile and the brushing effect of the apron may be exercised upon the tile principally during the time the tile is being 90 positively moved by the cross-bar against the direction of movement of the apron.

Various other modified adjustments or arrangements may be made, but it is not thought necessary to further describe them. 95

Adjacent to the forward spool 5, supporting apron 4, are mounted revolubly two pinch rolls 18 which conveniently have a covering of flexible or yielding material such for instance as soft rubber. These rolls are 100 revolubly mounted and adjustable to accommodate different thicknesses of tile, and they are driven by any suitable means in the direction shown by the arrows. They are set with their adjacent faces somewhat nearer 105 together than the thickness of the tile which are to be fed, so that they squeeze the tile and positively carry it in the feeding direction. 19 are two other pinch rolls, similar to 18, placed somewhat to the rear thereof. Between the two sets of pinch rolls are two cylindrical brushes 20, one above and one below the line of feed. These brushes are revoluble and are mounted adjustably so that they may be moved up or down in relation to the feed line. 110

20^a represents devices for adjusting the brushes and rolls.

The brushes are rotated by any suitable means in the direction of the arrows or 120 against the direction of movement of the tile. To the rear of pinch rolls 19 a second or rear brushing apron 21 is carried on spools 22 and driven in the direction of the arrow or oppositely to the feeding direction 125 by any suitable means. The upper surface of apron 21 is in substantially the same plane as that of apron 4 and apron 21 may be of

the same material as apron 4 or may vary in its characteristics as has already been pointed out in relation to the latter apron.

As the tile leave the rear end of apron 4 they are caught between pinch rolls 18 and carried between brushes 20 which brush both the upper and lower faces of the tile removing dust, dirt, etc. Pinch rolls 19 in turn catch the tile between them as they pass 10 from the brushes and deliver the tile upon apron 21 which supports them until they leave the machine. As apron 21 moves oppositely to the direction of feed it brushes the lower surface of the tile during their 15 contact with it.

The rear brushing apron 21 may in some cases be dispensed with, especially where the forward apron 4 acts as a brushing apron. When apron 4 acts simply as a feeding device 20 to free the tile in the box and does not perform a brushing function, rear apron 21 is usually provided to further clean the lower faces of the tile after they leave rotary brushes 20. The forward portion of the 25 machine, as shown diagrammatically in Fig. 1 may be employed without the rest of the mechanism and may be arranged to deliver the tile directly to the coating machine when it is not necessary to brush the tile or 30 when the lower surface only requires brushing. Without further description the possibility of using separate elements or combinations of elements of the invention without certain others will be apparent to persons skilled in the art.

The mechanism described is conveniently mounted upon a suitable framework so that it may be placed in operative position adjacent to or connected with a tile coating 40 machine at the feed end thereof. In Fig. 2 is shown a framework 23 carrying the feed and brushing mechanism and arranged to be secured by means of cap screws 24 or other suitable devices to the feed end of the frame 45 23 of a tile coating machine. Rear spool 22 and sprockets 10 are arranged adjacent to the forward spool 26 carrying the feeding apron of the coating machine. The mechanism of the feeding and dusting attachment 50 may be driven if desired by means of a belt 25^a passing over a pulley 25^b, which forms a part of the operative mechanism of the coating machine; but the feed and dusting machine may be driven by other means.

55 In some cases the rotary brushes may be dispensed with. When this is done only one brushing apron such as 4 is necessary, and this is made of appropriate length and arranged with its delivery end adjacent to the feeding apron of the coating machine.

Having described my invention, what I claim is:

1. The combination of a cleaning device, means for feeding tiles to said device, a coating device, and means for conveying tiles

from the cleaning device to the coating device.

2. In a machine of the class described, continuously moving means for removing tile singly from a group, for feeding the tile 70 in a linear direction, and for brushing the tile during their feeding movement.

3. In a machine of the class described, means for removing tile singly from a group, feeding the tile continuously and 75 positively in a linear direction, and brushing the tile during their feeding movement.

4. The combination of a receptacle for a stack of tile, a positive conveyer for moving tile, and a moving support for tile beneath 80 the conveyer.

5. The combination of an open-bottomed receptacle for holding one or more stacks of horizontally arranged tile, a continuous conveyer for removing tile singly from the bottom of the stack or stacks, and a support for tile beneath the conveyer.

6. The combination of an open-bottomed receptacle for holding one or more stacks of horizontally arranged tile, a positive conveyer for removing tile singly from the bottom of a stack or stacks, and a moving support for tile beneath the conveyer.

7. The combination of an open-bottomed receptacle for holding one or more stacks of 95 horizontally arranged tile, a continuous, positive conveyer for removing tile singly from the bottom of the stack or stacks, and a support for tile beneath the conveyer.

8. The combination of a tile feeding device 100 and a brushing device having a movement different from that of the feeding device for cleaning a surface of the tile.

9. The combination of a tile feeding device and a brushing device moving in a different direction from that of the feeding device 105 for cleaning a surface of the tile.

10. The combination of a tile feeding device and a brushing device moving in the opposite direction to that of the feeding device 110 for cleaning a surface of the tile.

11. The combination of a tile feeding device, and a brushing device serving as a support for the tile.

12. The combination of a tile feeding device, and a brushing device below the feeding line of the feeding device serving to support 115 and brush the tile.

13. The combination of a feed belt, and an apron beneath the belt serving to support 120 the tile.

14. The combination of a feed belt and an apron beneath the belt serving to support the tile, and having a different motion from that of the belt.

15. The combination of a feed belt and an apron beneath the belt serving to support 125 the tile and moving in the opposite direction to that of the tile.

16. The combination of a feed belt having 130

members which positively engage tile or the like, and an apron beneath the feed belt serving to support the tile.

17. The combination of a feed belt having 5 members which positively engage tile or the like, and an apron beneath the feed belt serving to support the tile and moving in an opposite direction to that of the belt.

18. The combination of a feed belt having 10 cross-bars for engaging the edges of tile or the like, and a tile supporting apron beneath the feed belt.

19. The combination of a feed belt having 15 cross-bars for engaging the edges of tile or the like, and a tile supporting apron having an exterior brushing surface.

20. The combination of a continuously impelled feed belt having cross-bars engaging the edges of tile or the like, and a tile 20 supporting apron beneath the feed belt continuously impelled at variance with the motion of the belt.

21. The combination of a continuously impelled feed belt having cross-bars engaging 25 the edges of tile or the like, and a tile supporting apron beneath the feed belt continuously impelled in the opposite direction to that of the belt.

22. The combination of a continuous, 30 moving feed belt having cross-bars engaging the edges of tile or the like, and a continuous tile supporting apron having an exterior brushing surface beneath the feed belt.

23. The combination of a feed belt having 35 members engaging the edges of tile or the like, and a support for tile beneath the belt having a brushing surface presented to the tile.

24. The combination of a feed belt having 40 members engaging the edges of tile or the like, a support for tile beneath the belt having a brushing surface presented to the tile, and means for supplying tile from a stack singly to the feed belt.

45 25. The combination of a feed belt having members engaging the edges of tile or the like, a support for tile beneath the belt having a brush surface presented to the tile, and a receptacle for supplying tile from a stack therein singly to the feed belt.

50 26. The combination of a coating machine comprising a feed apron, and feed mechanism comprising a holder for vertical stacks of tile or the like, and means for removing tile singly from the stacks and delivering them to the feed apron of the coating machine.

27. The combination of a holder for vertical stacks of tile, a rotary brush, and means 60 for removing tile singly from the stacks and passing them in contact with the brush.

28. The combination of a holder for stacks of tile, a support below the holder having a brushing surface, and means for removing

tile from the stacks singly and moving them 65 over the support in contact with the brushing surface.

29. The combination of a holder for stacks of tile, a support beneath the holder having a brushing surface, a rotary brush, and 70 means for removing tile singly from the stacks, passing them over the support in contact with the brushing surface and bringing them in contact with the rotary brush.

30. The combination of a holder for stacks 75 of tile, two separated supports, a rotary brush intermediate the supports, and means for removing tile singly and successively from the stacks, passing them in contact with the brush and delivering them success- 80 sively and continuously at the end of the second support.

31. The combination of a holder for vertical stacks of horizontally arranged tile, a continuous feed belt for moving the tile 85 passing below the holder and constructed so as to render the top and bottom surfaces of the tile accessible, a continuous apron moving in an opposite direction to that of the belt and below the holder and belt and close 90 to the latter forming a support for the tile, a second support for the tile removed from the first, two rotary brushes one on each side of the belt intermediate the supports, and pinch rolls at each side of the brushes for 95 grasping tile as they leave the first support, supporting them as they pass between the brushes and delivering them to the second support.

32. The combination of a holder for vertical stacks of horizontally arranged tile, a continuous feed belt for moving the tile passing below the holder and constructed so as to render the top and bottom surfaces of the tile accessible, a continuous apron moving in an opposite direction to that of the belt below the holder and belt and close to the latter and having an exterior brushing surface forming a support for the tile, a second support for the tile removed from the first, two rotary brushes one on each side of the belt intermediate the supports, and pinch rolls at each side of the brushes for grasping tile as they leave the first support, supporting them as they pass between the 115 brushes and delivering them to the second support.

33. The combination of a coating device, means for separating objects to be coated from a group, means for cleaning the objects, means for delivering them to the coating device and means for removing them from said device.

34. The combination of a coating device, a holder for groups of objects, automatic 125 means for removing objects from the holder and conveying them, means for brushing the objects after their separation from the group,

- and means for delivering the objects to the coating device and removing them therefrom.
35. The combination of a holder for groups of objects, a brushing device, a coating device and means for removing objects from the holder, passing them in contact with the brushing device, supplying them to the coating device and removing them therefrom.
36. The combination of a holder for groups of objects, a positive conveyer for removing objects successively from the holder, a brushing device having a movement different from that of the conveyer for cleaning a surface of the objects while they are moved by the conveyer, and a coating device arranged to apply coating to the objects delivered to it by the conveyer.
37. The combination of a holder for one or more groups of tile, a brushing support below the holder, a conveyer moving between the support and the holder and serving to remove tile from the holder successively, a coating device arranged to apply coating to the tile delivered to it by the conveyer and means for automatically removing the coated tile from the coating device.
38. The combination of means for holding a group of tile, a feed belt for moving tile from the group in one direction, and a supporting device for the tile moving in the opposite direction.
39. The combination of means for holding a group of tile, a feed belt for moving tile from the group in one direction, and a support and brushing device for the tile moving in the opposite direction.
40. The combination of a holder for groups of tile, a feed device for removing tile successively from the holder and means for freeing the tile in the holder.
41. The combination of a holder for groups of tile, a continuously moving feed device for removing tile successively from the holder and means for freeing jammed tile in the holder.
42. The combination of a holder for groups of tile providing considerable end clearance, a continuously moving supporting device tending to move the tile toward one end of the holder and a continuously moving feed device traveling below the holder and tending to move the tile toward the opposite end thereof.
43. The combination of a tile supporting apron having a brushing surface presented to the tile, and a feed belt moving above the apron and serving to carry tile over the apron and simultaneously brush them.
44. The combination of a tile supporting apron moving in one direction and having a brushing surface presented to the tile and a feed belt moving above the apron in the opposite direction.
45. In feed mechanism, the combination of a coating device, a feed box, a support below the box and a conveyer having adjustable devices to engage objects removed from the box, moving between the box and the support.
46. The combination of a coating machine including a feed apron, feeding mechanism comprising a holder for a group of tiles or the like, and means for separating tiles from the group and delivering them to the feed apron of the coating machine.
47. In tile cleaning and coating apparatus, the combination of means for automatically separating tile from a group, a cleaning device, a conveyer for supplying separated tiles to the cleaning device, and means for removing the tiles from the cleaning device.
48. In a machine for cleaning and coating tiles, the combination of a holder for a group of tiles, a cleaning device, means for removing tiles from the holder and delivering them to the cleaning device, a coating device, and means for conveying tiles from the cleaning device to the coating device.
49. The combination of a rotary brush, means for revolving it, a holder for groups of tiles or similar objects, means for separating tiles successively from the groups and delivering them to the brush and means for removing the tiles from the brush.
50. The combination of two rotary brushes, means for revolving them, a feed belt for delivering tiles or similar objects to the brushes so that the tiles pass between the brushes and a carry-off belt for moving the tiles from the brushes.
51. The combination of means for automatically separating tiles from a group, a brushing device, a conveyer for supplying the separated tiles to the brushing device and means for removing the tiles from the brushing device.
52. The combination of a brushing device, means for feeding tiles to said device, a coating device and means for conveying tiles from the brushing device to the coating device.
53. The combination of a holder for a group of tiles, a brushing device, means for removing tiles from the holder and delivering them to the brushing device, a coating device and means for conveying tiles from the brushing device to the coating device.
